UNITED STATES PATENT OFFICE

2,611,133

HALF SLIP

Irving L. Brown, New York, N. Y.

Application April 20, 1950, Serial No. 157,055

2 Claims. (Cl. 2—211)

1

This invention relates generally to new and useful improvements in garments for ladies and, in particular, to an improved undergarment or half-slip.

One of the important objects of the present invention is to provide an improved lady's undergarment consisting of a skirt or half-slip with a resilient waist portion to securely encircle the waist of the wearer and having secured thereto hosiery supporting means.

Heretofore, skirts or half-slips were found to be desirable to be worn with bare midriff dresses or the so-called two piece garments. Especially in summer wear, the practice of providing an exposed waist portion has been exceedingly popular with the cool comfortable features associated therewith. However, it has been necessary to utilize a second undergarment such as a garter belt to provide hose supporting means. This practice required the wearing of an additional undergarment and partially reduced the advantages gained by the use of the aforementioned articles of apparel.

The instant invention eliminates the need for the additional undergarment in that the hose supporting means are integral with the slip.

Another object resides in the provision of a combined half-slip and hose-supporting garment having a resilient waist portion that is constructed partially of lace-like material to provide ventilation and thereby further the comfort of the wearer.

Other ancillary objects will be hereinafter apparent from the following detailed description when read in the light of the drawings in which:

Fig. 1 is a perspective view of the garment on the body of a wearer illustrating in dotted line, a portion of the hose supporting means.

Fig. 2 is a sectional perspective view of the garment illustrating the features of the invention with a portion opened to show the construction thereof.

Fig. 3 is a plan view of the blanks used in constructing the garment, with the left-handed lace-like blank being shown. The right-handed lace-like blank, not shown, is identical to the illustrated blank.

Referring to Fig. 3, the blanks 10 and 11 are substantially similar and are provided with linear edges 12, 13 and 14, and 15, 16 and 17 respectively. The edges 12 and 13 of the blank 10, taper inwardly from the lower edge 14 thereof toward the upper linear edges 20 and 21. Intermediate the edges 20, 21 is a convexly arcuate edge 22.

In a similar manner, blank 11 has the edges 15, 16 thereof, tapered inwardly from the lower edge 17, toward the upper linear edges 23 and 24. Intermediate the edges 23 and 24 is a convex arcuate edge 25. The curved edge 25 being formed from the arc of a larger circle than the circle from which the arcuate edge 22 was formed.

10 Adjacent the upper edges of blank 10 is a blank 30 having linear edges 31, 32, 33, 34 and 35 thereon. The edges 32, 33 taper outwardly from the upper lateral edge 31 toward the lower lateral edges 34 and 35. Intermediate the lower edges 34, 35 is a concave arcuate edge 36.

15 Adjacent the upper edges of the blank 11 is a blank 40 having linear edges 41, 42, 43, 44 and 45. Intermediate the edges 44, 45 is a concave arcuate edge 46.

20 The lace-like blank 50 is substantially rectangular with linear edges 51, 52, 53 and 54 thereon. The edge 54 is substantially parallel to edge 52, however, the edge 54 is longer relative thereto and consequently, the edge 51 is inclined. The blank 50', Fig. 2, has identical dimensions to those of blank 50.

25 Adjacent the lower edges 14 and 17 of blanks 10 and 11 respectively are lace blanks 55 and 56. The blank 55 having edges 60, 61, 62 and 63 thereon and the blank 56 having edges 64, 65, 66 and 67 thereon.

30 As shown in Figs. 1 and 2, the blanks 10 and 11 are joined to form a unitary structure, the edges 13 and 15 thereof being joined along the stitch line 70 and the edges 12 and 16 being joined in a similar manner along the stitch line 71.

35 The blank 30 may then be secured to the blank 10, with the arcuate edges 22 and 36 being joined along the stitch line 72. The edges 34 and 35 are stitched to portions of edges 20, 21 respectively along the stitch lines 73, 74.

40 In a similar manner blank 40 is joined to blank 11, the arcuate edge 46 of the former being joined to the arcuate edge 25 of the latter along the stitch line 75. The edges 44, 45 are then secured to portions of the respective edges 23, 24 of the blank 11 along stitch lines 76, 77. The lace-like blank 50 may now be inserted. The edge 53 of the blank 50 is joined to the remaining portions of the combined edges 20, 24 along the stitch line 78. The vertical edges 52, 54 are joined to the respective edges 43, 32 along the stitch lines 79 and 80. The edge 53' of blank 50' is joined to the remaining portions of edges 21, 23 along 55 the stitch line 81 with the vertical edges 52' and

54' thereof joined to the respective edges 33, 42 along the stitch lines 82, 83.

Each of the resilient members 85, provided with conventional hose clips 86 are secured to the stitch lines 73, 74, 76 and 77, the reinforced construction thereof being ample to support the pressures exerted thereon.

To provide a snug-fitting waist, the blanks 30, 40 may have lateral resilient members 90 secured thereto which, when assembled and worn, secure the garment to the hips of the wearer.

The lace blanks 55, 56 are for ornamental purposes and are secured to the lowermost edges of the garment by suitable stitching lines.

Thus, it is obvious that the aforementioned garment will be cool, comfortable and possess utility. The snug-fitting portions, although ventilating, provide a smooth, pleasant appearance.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What I claim is:

1. A body garment comprising a skirt-like member formed from a plurality of blanks of material including front and rear lower blanks formed with upper and lower edges and with substantially straight, opposed vertical edges which are non-parallel and which are inwardly inclined toward their upper edges and which are joined together to form vertical side seams, the upper edges of said blanks being provided with central, convexly curved arcuate portions and substantially horizontal linear edges extending outwardly from the terminals of the curved portions, a plurality of upper blanks each having central concavely curved lower portions which are joined to the convexly curved arcuate portions of the front and rear blanks and having opposed inwardly inclined vertical edges and substantially horizontal linear lower edges extending outwardly from the terminals of the concavely curved portions which are joined to portions of the former linear edges, a plurality of blanks of lace-like material formed with substantially straight opposed vertical edges and upper and lower edges, the latter being joined

to the remaining portions of said former linear edges and having the vertical edges thereof joined to the vertical edges of the upper blanks, and hose supporting means secured to said lower blanks.

2. A garment comprising a skirt-like member formed from a plurality of blanks of material including front and rear lower blanks formed with upper and lower edges and with substantially straight, opposed vertical edges which are non-parallel and which are inwardly inclined toward their upper edges and which are joined together to form vertical side seams, the upper edges of said blanks being provided with central, convexly curved arcuate portions and substantially horizontal linear edges extending outwardly from the terminals of the curved portions, a plurality of upper blanks each having central concavely curved recesses on their lower edges which are joined to the convexly curved arcuate portions of the front and rear blanks and having opposed inwardly inclined vertical edges and substantially horizontal linear lower edges extending outwardly from the terminals of the concavely curved portions which are joined to portions of the former linear edges, a plurality of generally rectangular blanks of resilient lace-like material formed with substantially straight opposed vertical edges and upper and lower edges, the latter being joined to the remaining portions of said former linear edges and whose vertical edges are joined to the vertical edges of the upper blanks, the upper edges of the resilient blanks and the upper blanks forming the upper edges of the garment, and resilient hose supporting means secured to said lower blanks.
